UNITED STATES PATENT OFFICE.

HARRY W. HILL, OF CLEVELAND, OHIO.

MACHINE FOR STRAIGHTENING SHAFTS, TUBES, &c.

SPECIFICATION forming part of Letters Patent No. 606,214, dated June 28, 1898.

Application filed April 3, 1897. Serial No. 630,528. (No model.)

To all whom it may concern:

Be it known that I, HARRY W. HILL, a citizen of the United States, residing at Cleveland, in the county of Cuyahoga and State of Ohio, have invented certain new and useful Improvements in Machines for Straightening Shafts, Tubes, &c.; and I do hereby declare the following to be a full, clear, and exact description of the invention, such as will enable others skilled in the art to which it appertains to make and use the same.

The object of my invention is to provide a machine for straightening shafts, tubes, pipes, and other like cylindrical bodies which shall be simple in construction and efficient in operation.

Several styles of straightening-machines have been heretofore used. My machine is of the type wherein the straightening and draft rolls maintain a fixed relation to the main frame of the machine during the straightening operation. Some of these rolls are positively driven, with the result that they drag the shaft endwise between them and rotate and straighten it as it so moves. My invention consists of the combinations of parts by which this is efficiently accomplished, as is more fully hereinafter pointed out and as is definitely specified in the claims.

The drawings show the best embodiment of my invention at present known to me.

Figure 1 is an elevation of my improved machine, and Fig. 2 is a plan of the central portion thereof. Fig. 3 is a vertical section on the line 3 3 of Fig. 1, looking to the right of said figure, and thus being substantially an end view. Fig. 4 is a perspective view of one of the shaft-supporting carriages shown on a smaller scale in Fig. 1, and Fig. 5 is a plan of the same. Fig. 6 is an end view of said carriage, the parts shown askew in the two preceding figures being rectangled for convenience of illustration. Fig. 7 is a horizontal section on the line 7 7 of Fig. 1, being a bottom plan of the cross-head and straightening and draft rollers carried thereby.

Similar letters of reference designate similar parts in each figure.

Referring to the parts by letters, A represents the base of the machine, which is preferably a box-like structure, which should be securely bolted to the floor. The main driv-

ing-shaft F is mounted in a bracket a^7 , formed on the rear side of the base.

B represents a counter-shaft which extends longitudinally through the base, being journaled in boxes $a^1 a^2$ in the ends thereof, which boxes may be vertically adjustable to take up the stretch of the driving-chains. A shaft B', of smaller diameter than the counter-shaft proper, extends from each end of the latter a very considerable distance beyond the ends of the base, sufficiently far to enable it to perform the functions hereinafter described. Slow motion is transmitted from shaft F to shafts B and B' by means of the pinion f and gear b, which are secured, respectively, to said shafts.

Three pairs of draft-rolls G G are mounted in housings E, which are bolted in oblique positions upon the base in the manner substantially as shown, whereby the shaft X to be straightened (indicated by dotted lines in Fig. 1) will be supported by all of the said rolls and the axes of said rolls will be oblique to the axis of the said shaft X. To the shaft G of each of said draft-rolls a sprocket-wheel g² is secured. These housings and draft-rolls are of peculiar construction, which is of advantage, principally because it reduces their cost, particularly the cost of pattern-making.

Each housing consists of two sides or sections e e, which are exactly alike, and each consists of a horizontal base having on its inner edge a raised flange e⁴. These flanges are connected at their ends by bolts e². They are likewise offset near the bearing of one roll-shaft, wherefore the boss e³, in which is formed one bearing for one of the roll-shafts, is nearer the line of division between the housing-sections than the other bearing-boss e⁵.

The shafts g g are mounted in bearings in the bosses e³ e⁵. The rolls G and sprocket-wheels g² are placed on the shafts with the hub of the roll adjacent to the inwardly-extended boss e³, while the hub of the sprocket-wheel is adjacent to the boss e⁵. The rolls are thereby held in alinement with each other, while the sprocket-wheels are at opposite ends of the rolls, wherefore they cannot interfere with each other.

On each housing-section there is a sector-shaped upward extension e⁶ of the flange e⁴,

which is concentric with the adjacent roll, but of a slightly-smaller diameter, and this sector-shaped extension is adjacent to that part of the roll which is above its center and 5 toward the other roll. When the housing-sections are turned end for end, as shown, these two sector-shaped extensions lie on opposite sides of the plane passing between said rolls. If either roll-shaft should break, the 10 shaft X would temporarily be supported on one or both of these sector-shaped extensions.

Sprocket-chains g^3 transmit motion from sprocket-wheels b^2 , which are keyed to the counter-shaft B, to said sprocket-wheels g^2 , 15 whereby the draft-rolls G are driven positively. These chains will stretch in use, and therefore the boxes a' , in which said shaft is journaled, are made vertically adjustable. These boxes are secured to the ends of the 20 base by bolts a^2 , which pass through vertical slots a^3 in the base. The boxes are moved down to the desired position by set-bolts a^4 , which screw down through brackets a^5 on the ends of the base and bear upon said boxes. 25 This movement of the said shaft B changes its position relative to the shaft F, and unless such change of position were compensated for would effect the engagement of the two gears f and b . The shaft F is mounted eccentrically in a cylindrical sleeve a^6 , which may be turned in the brackets a^7 in the base, and they are so turned to cause said shaft F 30 to approach shaft B, and thus to compensate for the movement of the latter shaft. The sleeves are fixed in position by the set-screws a^8 , which screw through the brackets a^7 and impinge against said sleeves. 35

Secured to the base are four vertical standards H H H' H', which are united at their 40 upper ends in pairs by the transverse but slightly-oblique yokes J J'.

C represents a cross-head the ends of which embrace and are vertically movable upon the standards H H. C' represents a similar cross-head, which embraces and is movable upon the standards H' H'. Each of these cross-heads is formed of two plates c^c' , having in their proximate faces between their ends a recess c^2 , which is shown in Fig. 7 and in dotted lines in Fig. 3. The vertical tubular holes near the ends of these cross-heads through which the standards H H' pass are formed partly in both plates. The plates are secured together by bolts c^4 , by means of which the 50 plates may be made to tightly clamp the standards. On the outer sides of these plates are the horizontal perforated bosses $c^5 c^6$, which serve as bearings for the shafts d. The cross-head so stands that the axes of these bearings 55 are formed oblique to the axis of the shaft to be straightened, said obliquity being, however, in the reverse direction to the obliquity of the shafts g of the draft-rolls G G, but at substantially the same angle. The shafts d, 60 to which the upper pairs of draft-rolls are secured, are mounted in these bearings. These 65 upper pairs of draft-rolls D D are above points

which are between the lower pairs of draft-rolls, as shown in Fig. 1.

The cross-heads are moved up and down by 70 means of the two screws K K', which screw through the yokes J J' and are swiveled at their lower ends to said cross-heads. The upper ends of these screws support a cross-bar L, which bar loosely embraces the cylindrical 75 ends of the screws and rests upon the hubs of the gears k k', which are fixed to said screws. In the middle of this cross-bar a rotatable vertical shaft M is journaled, and it is supported by a collar m', fixed to it above the cross-bar. 80 On the lower end of this shaft a gear m is fixed, which gear meshes with the two gears k k'. A hand-wheel m² on the upper end of the shaft M furnishes means for rotating it, whereby both screws are simultaneously 85 turned to raise or lower the cross-heads equally.

The shaft to be straightened (indicated by X) rests upon and between the pairs of rolls G G. The rolls D D are caused to bear upon 90 the top of the said shaft with any desired pressure by the operation of the screws K K'. When the pressure is properly regulated and the draft-rolls G G are rotated as described, the shaft X and the upper draft-rolls D D are 95 likewise rotated and the shaft is drawn slowly endwise through the machine, being straightened as it so moves.

The ends of the shaft X are supported upon pairs of oblique draft-rolls R R, which are 100 mounted on carriages T with their axes parallel to the axes of the draft-rolls G G. The wheels of these carriages ride on tracks laid on the floor, and the carriages may be moved to any position in which they will be best 105 adapted to support the shaft. Each carriage is provided with a vertically-movable bolt adapted to engage in holes in the floor and thus hold the carriages from moving. These carriages consist of sides t' t', which are united 110 at their upper ends by the housings r of the draft-rolls. They are united near their lower ends by a cross-bar t², which furnishes a bearing for the counter-shaft B'. This cross-bar is provided at its ends with two laterally-extended flanges t³, in each of which is a vertical slot t⁴. (Shown by dotted lines in Fig. 4.) Bolts U pass through these slots and through the sides t', whereby this bar may be adjusted 115 vertically to preserve the alinement of the 120 shaft B'.

On the shaft of each of the draft-rolls R R is a sprocket-wheel r². On the shaft B' are sprocket-wheels b⁴, which are connected with the shaft by a spline, which permits them to 125 slide along the shaft, but which compels them to revolve with it. Sprocket-chains V V respectively connect one of the sprocket-wheels r² with one of the wheels b⁴, whereby the draft-rolls R R are positively driven. The draft-rolls R R not only help to support shaft X, but they also help to rotate it and move it endwise.

Having described my invention, I claim—

1. In a machine for straightening shafts, in combination, the obliquely-placed draft-rolls G G arranged in pairs and mounted upon a fixed base, the obliquely-placed upper draft-rolls D D likewise arranged in pairs between the lower pairs of draft-rolls, means for adjusting said upper draft-rolls vertically, and mechanism for positively driving one set of draft-rolls, substantially as specified.
- 5 2. In a machine for straightening shafts, in combination, a base, a shaft, sprocket-wheels secured thereto, pairs of draft-rolls mounted obliquely upon the base, independent sprocket-wheels rigid with said rolls, and sprocket-chains transmitting motion to the sprocket-wheels last named from those on the said shaft, upper pairs of obliquely-placed draft-rolls, and means for adjusting said upper draft-rolls vertically, substantially as 20 specified.
- 10 3. In a machine for straightening shafts, in combination, the base, pairs of positively-driven and obliquely-placed lower draft-rolls mounted upon said base, vertical standards, vertically-adjustable cross-heads which embrace and are guided by said standards, means for rigidly fastening said cross-heads to said standards, pairs of obliquely-placed draft-rolls mounted in said cross-heads, yokes 25 secured to said standards above said cross-heads, and adjustment-screws for moving said cross-heads, which screws are supported by said yokes, substantially as specified.
- 30 4. In a machine for straightening shafts, in combination, two vertically-movable cross-heads, pairs of draft-rolls mounted therein, vertical standards for guiding said cross-heads, yokes connecting their upper ends, screws working through said yokes and swiv-40 eled to said cross-heads and having cylindrical upper ends, gears secured to said screws, a cross-bar embracing the cylindrical parts of said screws and supported thereon, a vertical shaft mounted in and supported by said cross-bar, and a pinion secured to said screw in mesh with said gears, substantially as 45 specified.
- 45 5. In a machine for straightening shafts, in combination, a fixed base, pairs of obliquely-set draft-rolls mounted thereon, and vertically-adjustable pairs of oblique upper draft-rolls, a counter-shaft mounted in adjustable bearings, sprocket-wheels secured respectively to the said shaft and to the lower draft-50 rolls, sprocket-chains, a main driving-shaft, a cylindrical sleeve in which the latter shaft is eccentrically mounted, means for locking said sleeve to the base, and suitable connections between the two shafts, substantially as 55 specified.
- 60 6. In a machine for straightening shafts, in combination, the base, obliquely-set pairs of lower draft-rolls mounted thereon, vertical standards, cross-heads, each consisting of two plates bolted together and having in their proximate faces, near their ends, vertical grooves which embrace the standards, and,

between their ends, recesses for the reception of an upper pair of draft-rolls, pairs of draft-rolls mounted in said plates extending into 70 said recesses, and means for vertically adjusting said cross-heads, substantially as specified.

7. In a machine for straightening shafts, the combination of a base, a housing fixed 75 obliquely thereon and composed of two similarly-shaped sections e e, each of which has an inwardly-offset boss e³ surrounding one of the bearings of the roll-shafts, with two draft-roll shafts mounted in bearings in said hous-80 ing-sections, a draft-roll, and a rigidly-connected sprocket-wheel upon each of said shafts, the hubs of said rolls being adjacent to one of said inwardly-projecting bosses e³, and the sprocket-wheels being at the opposite 85 ends of said rolls, substantially as specified.

8. In a machine for straightening shafts, a draft-roll housing consisting of two sections of the same size and shape, each having on its 90 inner face an inwardly-offset boss e³, substantially as specified.

9. In a machine for straightening shafts, a draft-roll housing consisting of two sections of the same size and shape each consisting of 95 a horizontal base and a vertical flange on the inner edge of said base, which flange has the sector-shaped upward extension e⁶, and is also offset inward and provided on this inward offset with the boss e³, substantially as specified. 100

10. In a machine for straightening shafts, in combination, straightening devices comprising upper and lower pairs of obliquely-set draft-rolls, an operating-shaft, mechanism for transmitting motion therefrom to the 105 lower draft-rolls, an adjustable carriage having a bearing for said shaft and in which it may slide, a pair of obliquely-set draft-rolls mounted upon the carriage, and mechanism for transmitting motion from the shaft to 110 said draft-rolls, whereby the end of the shaft being straightened is supported and its longitudinal movement is assisted, substantially as specified.

11. A wheel-carriage for supporting a shaft 115 which is being straightened in a fixed straightening-machine, consisting of two side plates, a cross-bar extending between and secured to said plates and having a bearing for a shaft, a housing connecting the upper ends of said 120 plates, a pair of oblique draft-rolls mounted in said housing, sprocket-wheels secured to said rolls, a rotating shaft loosely mounted in said cross-bar and adapted to slide through the same, two sprocket-wheels secured upon 125 said shaft by a spline and groove, and sprocket-chains connecting the upper and lower sprocket-wheels, substantially as specified.

12. In a machine for straightening shafts, 130 in combination, a base, one set of lower draft-rolls arranged in pairs and mounted obliquely upon said base, a set of vertically-adjustable upper draft-rolls arranged obliquely and in

pairs, movable carriages on both sides of the base, obliquely-placed pairs of draft-rolls mounted on said carriages, a shaft mounted in the base and extended on both sides thereof, bearings carried by the carriages which support said shaft, whereby the carriages may be moved toward and from the base without changing their operative relation to said shaft, and mechanism for transmitting

motion from this shaft to the lower pairs of 10 draft-rolls on the base and to the draft-rolls on the carriages, substantially as specified.

In testimony whereof I affix my signature in presence of two witnesses.

HARRY W. HILL.
